UNITED STATES PATENT OFFICE.

GEORG ARTHUR SCHLOTTER, OF DRESDEN, GERMANY.

TURBINE.

Application filed November 12, 1921. Serial No. 514,741.

To all whom it may concern:

Be it known that I, GEORG ARTHUR SCHLOTTER, a subject of the Republic of Saxony, German Republic, and resident of Dresden, Republic of Saxony, German Republic, have invented a new and useful Improvement in Turbines, of which the following is a specification.

This invention relates to turbines and 10 more particularly to a turbine arrangement adapted to be acted upon both by suction and by a fluid under pressure.

The apparatus necessary for utilizing currents without any loss has heretofore 15 generally been arranged in such a manner that the impulsive force or thrust resulting from the speed of the currents was used for the transformation of energy, simultaneously avoiding as much as possible any formation 20 of eddies. For this reason, the turbines and the like apparatus employed were exposed to the currents without being placed in any casing or other surrounding enclosure.

25 An air-current axial flow turbine has also been proposed mounted in a casing of stream-line formation having a mouth-piece of vena contracta form and exhaust slots arranged around the casing in the rear of the turbine and adapted to utilize the entraining action of the air current flowing outside the casing.

30 Relatively to the said known arrangements of apparatus, turbines constructed and arranged according to the present invention are better adapted to utilize both the impulsive force of the currents and also their suction power and the current energy produced by the formation of eddies.

35 In the following description, the term "current stemming device" means a body so formed that the effect of a fluid current impinging upon the same, or of the impact of the body moving through a motionless fluid-medium, is to momentarily compact or compress the fluid, and thus cause a fluid-pressure at that side or part of the body receiving or making the first impact of or 40 against the fluid, and to create a partial vacuum at the opposite or near side or part of the body, thus causing a flow of the fluid from the first mentioned part to the second mentioned part of the body over or around the outer wall of the body at a velocity 45 higher than the average velocity of the fluid

current or than that of the body moving through a motionless fluid medium.

For the present purpose, with this improved kind of turbine construction, casings are necessary which are adapted to freely 60 permit the formation of eddies either as a suction-apparatus or as a current-stemming device.

An apparatus of the kind mentioned and arranged as a suction and current-stemming 65 device in its most suitable shape is a body of the stream-line type, the shape of which has been found by experiment, and according to the present state of the art of "stream-line" construction such a body is arranged 70 with its spherical head directed towards the current flowing so as to offer the smallest resistance.

In consequence of this fact, said body has 75 been defined as "a body of smallest resistance" or a "stream-line body".

The formation of a stream-line body in the manner described above is designed to utilize, as a working medium, the exterior currents which are stemmed so as to produce a compression or pressure in front of the head-part and thence circulate around the body with increased speed, in such a manner that said medium acts with suction effect on the interior chamber of the hollow body, owing to the said pressure suddenly falling over the enlarged edge of each annular nozzle-discharge aperture and thus 80 forming eddies. In this manner, a portion of the external fluid medium, or other gases 85 and liquids, is or are drawn by suction through the interior of the casing, and a steady current is thus produced within the casing at a much higher speed than that of 90 the outer current.

95 The admission apertures leading into the interior of the apparatus are arranged in the spherical or elliptical head-piece and, according to its use and purpose in view, may 100 be arranged laterally or at the middle part in the direction of the longitudinal axis, said apertures also being nozzle shaped with their smaller diameter directed towards the interior chamber of the apparatus. If one 105 nozzle is arranged in the central part of the head co-axial with the longitudinal axis of the casing, it is preferable to arrange it in such a manner that its admission area is not larger than the half of the largest cross 110 sectional area of the head. In this manner,

the necessary current stemming or pressure producing surface is obtained for the incoming current of the working medium.

The apparatus can be elongated axially 5 preferably by elongating the part of maximum diameter, for the purpose of enlarging the inner chamber and for arranging several annular nozzles. For the purpose of ensuring a simpler and easier construction of 10 the apparatus, especially in the case of large dimensions, a polygonal shape may be adopted instead of the circular shape described above.

Apparatus constructed in accordance with 15 the invention is illustrated in the accompanying drawings, in which—

Fig. 1 is a longitudinal sectional view of a casing of a "stream-line" form for a 20 turbine arrangement constructed according to the invention.

Fig. 1^a is a detail longitudinal section of a modified form of head piece.

Fig. 2 is a plan view as seen from the 25 under side of the casing shown in Fig. 1.

Fig. 3 is a transverse section taken on the line A B of Fig. 1.

Fig. 4 is a transverse sectional view of an octagonal casing.

Fig. 5 is a longitudinal sectional view of 30 a turbine mounted in a casing of the kind shown in Fig. 1.

Fig. 6^a-6^b is a longitudinal section illustrating another modified form of turbine arrangement.

Referring to Figs. 1 to 4, the curved line 35 a—b—a represents the fundamental form of a body offering the least resistance. The body forming the turbine casing consists of the head-piece *k* and the terminal points *s*. The head-piece *k* as shown in Figs. 1 and 2 is of spherical shape, while Fig. 1^a represents a detail section of a head-piece of elliptical shape.

Between the head-piece *k* and the terminal point *s* rings *r*, projecting one into another, are arranged, of which the ring situated nearest to the head-piece is rigidly connected with the latter in such a manner that on

adjusting the terminal point *s* movably supported within the turbine casing, the annular space existing between the last ring and the last ring but one can be changed or altered. The rings *r* which are shown as being inserted one into another to an extent shown at *v* are provided with enlargements situated on the outer edges of said rings and gradually increasing towards the point *s*, thus forming the annular nozzle chambers *d* which gradually increase in length towards the point *s* and are not reduced in section by the said enlargements. The thickened parts *i* (Fig. 1) at the inner edges of the rings *r* are directed towards the axis 55 of the apparatus. The head-piece, the rings and the point are connected together by the

main longitudinal ribs *p* so as to form a complete body.

The apparatus is preferably provided with a pillar or post *t* of oval shape adapted to the shape of the stream line body and can 70 be turned around with said body to adjust its longitudinal axis into the direction of the currents. Said pillar or post *t* can also serve as a lateral admission opening for drawing in other gases and liquids by 75 suction as mentioned above. For this purpose, the head-piece must be closed in the direction of the longitudinal axis, as represented by the spherical periphery shown by the dotted and pointed line *e* on the right side 80 of Fig. 1. *u* is an axial nozzle through which the working medium is admitted and which is represented in Fig. 1 with the most effective diameter for the utilization of the currents. 85

If it is intended to use the apparatus described for the utilization of the current energy of the medium or liquid surrounding it and to advantageously profit by the sucking power of said medium or liquid, 90 it will be necessary to arrange a turbine-wheel within the casing of the apparatus, in which a zone of diminished pressure is created by the sucking power of the eddy currents flowing around the casing. Said zone of diminished pressure acting in conjunction with the pressure of the external fluid current will impart to the liquid current entering the hollow chamber of the 95 casing a velocity corresponding to the difference of pressure, the energy of which is utilized by the turbine wheel arranged in the rear of the nozzle. 100

Referring to Fig. 5 of the drawings, *n* is the turbine wheel used for the utilization of the energy and arranged in the inner chamber of the suction casing *k*, said wheel being rotated or driven by the fluid current entering through the nozzle *u*. The 105 energy obtained can be transmitted to other machines or apparatus by the dynamo *m* coupled with the turbine wheel on a common shaft. 110

The utilization of eddy currents by turbine wheels is only possible in the case of annular eddies which are produced in the rear of each obstruction placed or inserted in the path of a current. But said obstruction must, according to the purpose aimed at, be of a circular or polygonal shape so as to form at its rear surface annular eddies. 115

Fig. 6^a-6^b represents in longitudinal section this duplex turbine arrangement together with the complete apparatus. In this arrangement the turbine *n*, shown in Fig. 6^a on the left, is mounted within the interior of the suction body *k* for the currents entering through the nozzle *u* of the head-piece under the suction action of the 120 125 130

external eddy currents. The end of the casing is so shaped that a discharge-part is formed with a circular bent-up part x designed to deflect and stem the fluid circulating around the casing for the purpose of providing the eddies for the eddy current-turbine.

The current of the annular eddy formed in this arrangement and ensured against unstable equilibrium by the central annular roll z and the point of the centre piece h is utilized by the turbine n^1 arranged outside of the casing k , as shown in Fig. 6^b on the right.

The wheel of the eddy turbine can advantageously be provided with two crowns to utilize not only the energy of the annular eddy but also a part of the suction energy of the current by the connection of said wheel with the suction chamber.

This modified arrangement also is shown in Fig. 6^b in connection with one-half of the whirl-turbine. $n^1 w^1$ is the crown for the utilization of the eddy energy, whereas the wheel-crown $n^1 s^1$ mounted nearer the shaft enables the suction energy to be utilized in the same manner as the forward interior turbine n .

Both turbines can, for the purpose of a mutual control of the speed of the rotary movement and of a simple power-transmission, be advantageously connected with the dynamo m by a common shaft y , as shown.

The complete apparatus is supported on a rotatably arranged post t and held in a position co-axial with the suction nozzle u and with the eddying outer currents.

What I claim is:

1. In a turbine arranged as suction and fluid current stemming apparatus, the combination with rings arranged one within another, of annular chambers each of which is situated between two adjacent rings and which are outwardly directed with their smallest openings in the shape of nozzles by a decrease of the diameters of the separate rings towards the point of the turbine, said rings increasing in section towards the point mentioned.

2. In a turbine arranged as suction and fluid current stemming apparatus, the combination with rings arranged one within another, of annular chambers each of which is situated between two adjacent rings and which are outwardly directed with their smallest openings in the shape of nozzles by a decrease of the diameters of the separate rings arranged one within another towards the point of the turbine, said rings increasing in section towards the point mentioned.

3. In a turbine arranged as suction and fluid current stemming apparatus, the combination with rings arranged one within another, of annular chambers each of which

is situated between two adjacent rings and which are outwardly directed with their smallest openings in the shape of nozzles by a decrease of the diameters of the separate rings arranged one within another towards the point of the turbine, said rings simultaneously increasing in section towards the point mentioned and being provided on their inner edges with thickened parts inwardly inclined towards the shaft of the turbine and tapering outwardly, and on their outer edges with enlargements increasing in section towards the point of the turbine.

4. In a turbine arranged as suction and fluid current stemming apparatus, the combination with rings arranged one within another, of annular chambers each of which is situated between two adjacent rings and which are outwardly directed with their smallest openings in the shape of nozzles by a decrease of the diameters of the separate rings arranged one within another towards the point of the turbine, said rings simultaneously increasing in section towards the point of the turbine and being provided on their inner edges with thickened parts inwardly inclined towards the shaft of the turbine and tapering outwardly, and on their outer edges with enlargements increasing in section towards the point of the turbine, which point is adjustable with the adjacent ring.

5. In a turbine arranged as suction and fluid current stemming apparatus, the combination with rings arranged within one another, of annular chambers each of which is situated between two adjacent rings and which are outwardly directed with their smallest openings in the shape of nozzles by a decrease of the diameters of the separate rings arranged one within another towards the point of the turbine, said rings simultaneously increasing in section towards the point of the turbine and being provided on their inner edges with thickened parts inwardly inclined towards the shaft of the turbine and tapering outwardly, and on their outer edges with enlargements increasing in section towards the point of the turbine, of an adjustable ring situated towards the point and a turbine wheel arranged within the turbine casing.

6. In a turbine arranged as suction and fluid current stemming apparatus, the combination with rings arranged within one another, of annular chambers each of which is situated between two adjacent rings and which are outwardly directed with their smallest openings in the shape of nozzles by a decrease of the diameters of the separate rings arranged one within another towards the point of the turbine, said rings simultaneously increasing in section towards the point of the turbine and being

provided on their inner edges with thickened parts inwardly inclined towards the shaft of the turbine and tapering outwardly, and on their outer edges with enlargements increasing in section towards the point of the turbine, of a turbine wheel arranged on the point of the turbine casing formed as a discharge part having a circular bent portion for the regulation of the nozzle-shaped openings, and two turbine-

wheels connected within the common casing formed by the outer turbine, the said casing serving simultaneously to produce a suction for the interior turbine-wheel and as an eddy producing means for the exterior turbine-wheel. 15

In testimony, that I claim the foregoing as my invention, I have signed my name.

GEORG ARTHUR SCHLOTTER.
